UNITED STATES PATENT OFFICE.

GIDEON RIETVELD, OF KNOXVILLE, IOWA.

MAIL BOX.

Application filed March 22, 1927. Serial No. 177,332.

The object of my invention is to provide a mail box of simple, durable and inexpensive construction designed to be constructed of sheet metal with suitable dies and formers, and formed substantially of two members, each alike, so that both may be formed from the same set of dies.

More specifically it is my object to provide a mail box of this kind in which the 10 spring actuated newspaper holder on the exterior of the mail box may coact with the mail box proper for hinging the two members thereof together, and also coact with the spring for normally holding the movable box member in closed position, and at the same time apply a suitable yielding pressure to the newspaper holder.

My invention consists in the construction, arrangement and combination of the various parts of the device, whereby the objects contemplated are attained, as hereinafter more fully set forth, pointed out in my claims, and illustrated in the accompanying drawings, in which:

25 Figure 1 shows a side elevation of a mail box embodying my invention in open position.

Figure 2 shows a vertical, central, sectional view of my improved mail box in 30 closed position.

Figure 3 shows a bottom view of same illustrating the arrangement of the newspaper holder and spring for closing the mail box.

35 Figure 4 shows a detail sectional view on the line 4—4 of Figure 2; and

Figure 5 shows a detail sectional view on the line 5—5 of Figure 2.

Referring to the accompanying drawings, 40 it will be seen that the mail box is composed of two members, one being the back or stationary member and the other the front or movable member.

The back member is formed of a straight 45 flat rear body portion indicated by the numeral 10. Formed integral with its side edges are the side members 11, formed by bending the sheet metal forwardly at right angles to the back. At the top these side 50 members 11 are rounded as shown at 12, and the rounded ends are inclined inwardly and upwardly, as shown at 13 in Figure 4. The top, indicated by the reference numeral 14, is curved upwardly and then inwardly and 55 is of less length than the sides 11, as clearly shown in Figure 2. The bottom 15 is also

curved upwardly and inwardly and is of less length than the sides 11. The bottom of the sides 11 extends downwardly below the bottom member 15 and is curved at its lower end and indicated by the numeral 16. Formed in the back member 10 are two openings 17 through which screws or nails may be inserted to permanently fix the back member to an upright support.

The front member is substantially an exact counterpart of the back member, so much so that each may be made from the same set of dies and formers. In the drawings the front of the mail box is indicated by the symbol 10^a, the sides 11^a, the upper ends of the sides 13^a, the top 14^a, the bottom 15^a and the extension at the lower ends of the sides 16^a.

When these two members are formed from the same dies and formers and forced into the position shown in Figure 2, the sides 11, the top 14 and the bottom 15 of the back are caused to bend inwardly to a slight degree and the corresponding parts of the front member are caused to bend outwardly to a slight degree so that the two may telescope, as shown in the drawings. The metal of which the mail box is formed is quite thin and the two parts may be thus telescoped without being especially formed for that purpose, and being made on the same dies, but if thicker or stiffer metal is used, it may be desirable to first bend the several parts to the desired position so they will 75 telescope readily and easily and lie in their proper relative positions, and even if very thick metal is used, the two parts may be constructed on the same dies and formers and after being thus constructed a slight 80 amount of bending will suffice to make them 85 properly telescope, as shown in the drawings.

In order to pivotally connect the two mail box members, I provide a newspaper holder indicated generally by the reference numeral 18, having its central portion formed in the shape of a curved tongue designed to rest against the front lower portion of the mail box, and its ends inclined rearwardly 100 and extended horizontally at 19, and then inwardly toward each other at 20 through suitable openings formed in the parts 16 and 16^a, as shown in Figure 5, so that these 105 inwardly extending members 20 form a hinge connection at the bottom between the front and back members.

It is desirable that this newspaper holder be yieldingly held with its upper end portion adjacent to the front 10^a and it is also desirable that a spring be provided for normally closing the front. For this purpose, I have provided a coil spring 21 mounted in the space below the curved bottom member 15, as shown in Figure 2, and surrounding the ends 20 of the newspaper holder. One end of the spring at 22 is extended rearwardly and engages the bottom of the back member of the mail box, and the other end 23 is extended forwardly and engages the newspaper holder, as shown in Figure 3. By this arrangement it is obvious that the newspaper holder performs the double function of holding newspapers and forming a pivot or hinge for the mail box members, and the spring performs the double function of closing the mail box and at the same time yieldingly holding the newspaper holder toward the front of the mail box. Furthermore, these two members are so arranged and combined that they may be assembled with each other and with the mail box without any screws, bolts or other fastening devices.

By forming the bottom members 15 and 15^a in the manner illustrated in Figure 2, it is obvious that when the front is swung forwardly and letters placed in the box, they will rest upon the upper curved member 15^a, and then when the front is closed, they may tilt to various angles within the mail box at their tops, but the lower ends will always rest on the member 15^a and not become caught between the members 15 and 15^a during the opening and closing movements.

The structure of the top of the mail box is advantageous in that by bending the upper ends of the side members inwardly and upwardly, as shown in Figure 4, and by curving the tops 14 and 14^a in the manner shown in Figure 2, these parts will telescope readily when closed, and at the same time form a rain proof cover. In Figure 4 it will be seen that rain driven against the mail box from the side will be deflected by the top member 14^a and the inclined outer member 13^a.

From the foregoing it will be seen that I have provided a mail box of extremely simple and inexpensive construction, in which the two essential members may be formed from the same set of dies, and in which the newspaper holder and spring may be assembled without screws or bolts or other fastening devices, and at the same time a

mail box that is rain proof is provided, and the hinged front is yieldingly held in closed position, and at the same time the proper yielding pressure is applied to the newspaper holder, thus forming a highly efficient and durable mail box.

I claim as my invention:

1. In a device of the class described, the combination of a sheet metal back member having its sides extended forwardly and having its top curved upwardly and forwardly and its bottom curved upwardly and forwardly, a front member formed substantially identical with the said back member and having its sides, top and bottom telescopically connected with the corresponding parts of the back member, and means for hinging together the downwardly extended ends of the side members.

2. In a mail box, the combination of a front and a back member forming a box, a newspaper holder device formed of wire having a body portion designed to stand in front of the box and having side members extended rearwardly, and end members extended inwardly toward each other and designed to pass through portions of the front and back members to form a hinge connection between said members, a coil spring arranged below the mail box and encircling the end members of the newspaper holder, one end thereof being extended rearwardly to engage the bottom of the mail box, the other end being extended forwardly to engage the newspaper holder in front, and whereby the spring will yieldingly hold the upper end of the newspaper holder against the front of the mail box and at the same time exert its pressure tending to close the front member of the mail box.

3. In a device of the class described, the combination of a sheet metal back member having its sides extended forwardly, and having its top curved upwardly and forwardly and its bottom curved upwardly and forwardly, and also having the upper end of its sides extended upwardly and inwardly and the bottom member of its sides extended downwardly, a front member formed substantially identical with the said back member and having its sides, top and bottom telescopically connected with the corresponding parts of the back member, and means for hinging together the downwardly extended ends of the side members.

Des Moines, Iowa, March 15, 1927.

GIDEON RIETVELD.
